UNITED STATES PATENT OFFICE.

JAMES L. EDWARDS, OF DALLAS, TEXAS.

STEAM-ENGINE.

1,304,864.

Specification of Letters Patent. Patented May 27, 1919.

Application filed January 18, 1918. Serial No. 212,428.

To all whom it may concern:

Be it known that I, JAMES L. EDWARDS, a citizen of the United States, residing at Dallas, in the county of Dallas and State 5 of Texas, have invented certain new and useful Improvements in Steam-Engines, of which the following is a specification.

This invention relates to new and useful improvements in steam engines.

10 The main features of the invention are the production of an engine in which back pressure is substantially eliminated and a speed of from three hundred to six hundred revolutions may be had and also one in 15 which no eccentrics or stuffing boxes are used.

In carrying out the invention an engine is constructed with an odd number of cylinders and their pistons so connected with the 20 crank shaft that the engine will not stop on "center."

The invention will be more readily understood from a reading of the following specification and by reference to the accompanying drawings, in which an example of 25 the invention is illustrated, and wherein,

Figure 1 is a longitudinal sectional view of an engine constructed in accordance with this invention,

30 Fig. 2 is a transverse sectional view on the line 2--2 of Fig. 1,

Fig. 3 is a transverse sectional view on the line 3--3 of Fig. 1,

Fig. 4 is an end elevation showing the 35 governor control for the steam valve,

Fig. 5 is a side elevation of the same,

Fig. 6 is an end elevation showing the 40 valve operating means,

Fig. 7 is a detail of the steam valve,

45 Fig. 8 is a cross section of the same,

Fig. 9 is a detail of the exhaust valve,

Fig. 10 is a detail of the same and,

Fig. 11 is a diagrammatical view showing the 50 relation of the cranks of the crank shaft.

45 In the drawings the numeral 1 designates an engine block in which three upright cylinders 2, 3 and 4 respectively are formed and covered by a cylinder head 5 which covers the entire block. A longitudinal 55 steam chamber 6 is formed in the block along one side of the cylinders while the ex-

haust chamber 7 is formed along the other side of said cylinders as shown. The chamber 6 has communication with each cylinder through an individual port 8 and each cylinder communicates with the exhaust chamber through individual ports 9 and 10 respectively. The ports 8 and 10 are located at the bottom of the cylinders while the ports 9 are located near the top of each cylinder. 60

Communication between the chamber 6 and the ports 8 is controlled by a longitudinal rotary valve 11 interposed therebetween. This valve as shown in detail in Figs. 7 and 65 8 has recesses 12 in its surface disposed so as to register with the ports 8 during a portion of the rotation of the valve, said ports being closed by the surface of the valve during the other portion of the rotation. 70

I have shown an engine having three cylinders and a valve having three recesses each separated by suitable packing rings 13 and disposed on thirds with relation to the rotation whereby the port 8 of each cylinder 75 will be opened for communication with the steam chamber once during each rotation of the valve and whereby a port will be opened at each third of a revolution. The steam valve is provided with an oscillating segmental packet 14 which may be adjusted so as to close a portion of the ports 8 and thus control the volume of steam admitted to the cylinders. On the head standards 15 are mounted transversely and support a crank 80 shaft 16 projecting beyond the block 1 and carrying a momentum wheel 17 on one end and a beveled gear 18 on the other end. On the crank shaft between the wheel 17 and the adjacent standard 15 an ordinary centrifugal governor 18 is mounted and connected with a bell crank lever 19 pivoted on a support 20 mounted on the block. An arm 21, connected with the jacket 14, extends transversely across the end of the block and 85 engages in a rocker 22 mounted on a bracket 23 and having its opposite end connected with the bell crank lever by means of a link 24. When the crank shaft revolves above the proper speed the governor is operated in 90 100 the usual way and swings the lever 19, as shown by the arrows in Fig. 5, with the re-

sult that the arm 21 is swung upward as indicated in Fig. 4 and the jacket 4 rocked to reduce the area of the ports 8 and thus cut down the volume of steam.

5 Pistons 2', 3' and 4' are disposed in the cylinders 2, 3 and 4 respectively. Each piston has a piston rod 25 extending up through the head 5. The crank shaft 16 has cranks 26 disposed at equal distance and 10 relatively on thirds of a circle as indicated in Fig. 11. Each crank has connection with a piston rod by a link 27. It will be seen that steam enough passes above the piston and therefore no stuffing boxes are required 15 for the piston rods.

The passage of exhaust steam through the ports 10 is controlled by a rotary exhaust valve 28 having recesses 29 set on thirds and positioned to register with said ports. The 20 ports 9 are always in communication with the exhaust chamber 7 so that no pressure can be accumulated above the pistons on their upward strokes and any steam which does not readily escape through the ports 10

25 may pass out through the ports 9. For operating the valves a vertical shaft 30 is mounted on the end of the block 1 and carries a pinion 31 meshing with the gear 18 and at its lower end is provided with a pinion 32 positioned to mesh with either of a pair of beveled gears 33 slidably confined on a transverse shaft 34 and adjustable by means of a lever 35. The gears 33 are spaced so that only one can mesh with the pinion 32 at a time, and thus when the shaft 34 is revolving in one direction it may be reversed by shifting the said gears. The shaft 34 carries beveled pinions 36 at each end. One of these pinions engages with a 40 beveled gear 37 mounted on the trunnion 38 of the steam valve 11 while the other meshes with a beveled gear 39 fixed on the trunnion 40 of the exhaust valve 28. The gears are so proportioned and related as to 45 cause the valves to complete one rotation during each rotation of the crank shaft. By this means the eccentricities are eliminated.

In starting the engine live steam is admitted to one cylinder and when the steam 50 is cut off and begins to expand live steam is admitted to another cylinder and the exhaust of the other is opened. During each complete rotation of the crank shaft live steam is admitted during each successive 55 third of a revolution to a different cylinder and from this it will be seen that the engine is constantly receiving live steam and is constantly utilizing the expansive force and that two cylinders are always active. Referring to Fig. 1 it will be seen that the piston 2' is just starting on its upward stroke and piston 3' is completing its upward stroke while piston 4' is on its downward stroke. Live steam is being admitted 60

to cylinder 2 but is cut off from the other 65 cylinders. The piston 3' is being driven upward by the expansive force of the steam and the piston 4' is moving down and the cylinder exhausting, the exhaust ports 10 of the cylinders 2 and 3 being closed and the 70 exhaust port 10 of the cylinder 4 being open. When the piston 4' reaches the end of its down stroke the valves will be shifted so as to close the port 10 of cylinder 4 and open the port 10 of cylinder 3 while the 75 steam valve will be adjusted to cut off the supply of live steam to cylinder 2 and open the port 8 of cylinder 4; whereby piston 2' will be impelled by the expansion of the steam in its cylinder and live steam will be 80 admitted to cylinder 4 it is obvious that two cylinders will always be active and the engine can not stop on a so-called "dead center."

The foregoing description and illustration clearly express the invention, but it is to be understood that said illustration is merely an exemplification and the invention may be carried out in various other ways.

What I claim is:

1. In a steam engine, the combination of an engine block having vertical cylinders and a live steam chamber on one side of the cylinders and an exhaust chamber on the other side, each cylinder having a live steam 95 port at its bottom communicating with the live steam chamber, and also an exhaust port at its bottom and another exhaust port near its top both of which communicate with the exhaust steam chamber, a cylinder 100 head mounted on the block, pistons mounted in the cylinders and having rods extending through the head, a crank shaft supported above the head and having offset cranks connected with the piston rods of the pistons, a rotary steam valve interposed between the live steam chamber and the live steam ports, a jacket movable relatively of the steam valve for varying the area of the live steam ports, a rotary exhaust valve interposed between the exhaust steam chamber and the lower exhaust ports, a gearing 110 connecting the crank shaft with the rotary valves, whereby said valves and crank shaft each complete a revolution in unison, and 115 a governor mounted on the crank shaft and connected with the jacket for operating the same.

2. In a steam engine, the combination with an engine block having vertical cylinders and a live steam chamber on one side of the cylinders and an exhaust chamber on the other side of said cylinders, the cylinders having ports communicating with the chambers, a rotary exhaust valve controlling the passage of steam through the exhaust ports, a rotary steam valve, a rocking jacket controlling the passage of steam from

the steam valve through the inlet ports of the cylinders, a crank shaft mounted above the cylinders, and pistons connected with and operating the crank shaft, of a governor 5 operated by the crank shaft and having connection with the steam valve jacket for rocking the same, a prime mover operated by the crank shaft, a reverse element driven by the prime mover and constructed to be shifted to reverse motion, and driving connections between the reversing element and the valves.

In testimony whereof I affix my signature.

JAMES L. EDWARDS.
